Primary Examiner—Raphael Barkai*Attorney, Agent, or Firm*—Thomas W. Tolpin[57] **CLAIM**

The ornamental designs for a core for high performance in-line roller skate wheel, as shown and described.

DESCRIPTION

FIG. 1 is a perspective view of a core for high performance in-line roller skate wheel showing my new design;

FIG. 2 is a front view thereof, the back view being identical thereto;

FIG. 3 is a right side view thereof, the left side view, top view, and bottom view being identical thereto;

FIG. 4 is a front view of another core for a high performance in-line roller skate wheel showing my new design, the back view being identical thereto; and,

FIG. 5 is a right side view thereof, the left side view, top view, and bottom view being identical thereto.
